(57) **CLAIM**

The ornamental design for a display screen with graphical user interface, as shown and described.

DESCRIPTION

FIG. 1 is a front view of a first embodiment of a display screen with graphical user interface showing my new design;

FIG. 2 is a front view of a second embodiment of a display screen with graphical user interface showing my new design; and,

FIG. 3 is a front view of a third embodiment of a display screen with graphical user interface showing my new design. The broken line showing of the display screen, text, and portions of the graphical user interface in FIGS. 1 through 3 illustrates the environment of the claimed design and forms no part thereof.
